WERNER LEHMAN, OF SOUTH MILWAUKEE, AND TREVOR DAVIDSON, OF MILWAUKEE, WISCONSIN, ASSIGNORS TO BUCYRUS-ERIE COMPANY, OF SOUTH MILWAUKEE, WISCONSIN, A CORPORATION OF DELAWARE

BOOM SUSPENSION

Application filed July 28, 1928. Serial No. 296,028.

Our invention relates to new and useful improvements in boom suspensions.

Power shovels are well known in the excavating art. They consist in a main frame, 5 with a boom pivoted at its foot to the frame and suspended by means of tension members connecting its outer end to an elevated point on the frame. About half way up the boom is a shipper shaft, on which a dipper handle 10 reciprocates and swings in a vertical plane. Various alternative means are employed to accomplish this swinging and reciprocating, but these means are not involved in the present invention. At the outer end of the handle 15 is a digging dipper.

The principal object of our invention is to provide a novel form of boom suspension, such that the weight of the boom will be properly distributed on the suspending members, and any twist imparted to the boom by the 20 sidewise motion of the dipper will be properly taken up and resisted, and yet a certain degree of flexibility of the boom will be maintained.

Further objects and advantages of our invention will be readily evident, as the description progresses.

The invention consists in the novel parts, and in the combinations and arrangements thereof, which are defined in the appended claims; and of which one embodiment is exemplified in the accompanying drawings, which are hereinafter particularly described and explained.

Throughout the description, the same reference number is applied to the same member or to similar members.

Figure 1 is a side elevation of so much of a power shovel as is necessary to illustrate our 40 invention.

Figure 2 is a plan view of the reeving of ropes shown in Figure 1.

Referring to the drawings, it will be seen that 3 is the main frame of a power shovel, 45 supporting the boom 4, the A-frame 5 and the boom hoist winch 6.

On a bracket 7 on the boom 4 is mounted a shipper shaft 8, carrying a saddle-block 9 through which the dipper-handles 10 reciprocate, and which pivots about the shipper

shaft 8, thus enabling the dipper-handles 10 to swing in the vertical plane which contains the boom 4. The digging-dipper, mounted on the lower end of the handles 10, and the means for swinging and reciprocating the handles, are not shown, being immaterial to our present invention, and being well known in the art.

The boom is raised and lowered by means of the winch 6 and a boom-hoist cable 11, which passes from the winch over a sheave 12 at the apex of the A-frame 5, thence over a sheave 13 at the point of the boom, thence over a sheave 14 at the apex of the A-frame, thence over a sheave 15 at the point of the boom, thence around two sheaves 16 and 17 on a yoke 18 attached to the apex of the A-frame, thence over a sheave 19 at the point of the boom, thence over a sheave 20 at the apex of the A-frame, thence over a sheave 21 at the point of the boom, thence over a sheave 22 at the apex of the A-frame, and hence to an anchorage 23 on the last reach of the rope itself. It will be readily seen that the rope 11 thus constitutes an eight-reach hoist for the boom. This exact method of hoisting the boom is not a feature of our invention.

Although it is conventional to employ the boom-hoist cable to perform the function of suspending the boom after it has been hoisted, distinct means are provided by us for this purpose, and our invention inheres in these means. The boom is shown in Figure 1 in its hoisted position.

There are two boom-suspension cables, 24 and 25. Each passes from an anchorage 26 on the end of the shipper shaft 8, thence around a sheave 27 near one extreme side of the apex of the A-frame 5, thence around a sheave 28 at the point of the boom, and thence back to an anchorage 29 adjacent the sheave 27. In the present exemplification of our invention, it happens that this anchorage 29 and the sheave 27 are formed integral, as the rope 24, being a mere support, rather than a running rope, does not require a sheave capable of rotation. It is to be noted that the anchorages 26 are widely spaced apart from each other, by virtue of their locations at the ends of the shipper shaft 8.

In order to simplify a study of the rather complicated reeving, diagrammed in Figures 1 and 2, the boom-suspension ropes 24 and 25 have been drawn considerably broader than 5 the boom-hoist rope 11.

It will be noticed that each of the boom-suspension ropes 24 and 25 constitutes a two-reach support for the outer end of the boom, and a one-reach support for the center of the 10 boom.

The reasons for our particular form of boom-suspension will be readily evident from the following history of the successive inventive steps required to solve the present problem. The main support of the boom must, of course, be at its outer end, as that is where practically all of the load of the dipper and contents is to be carried. But, with the very long booms on the enormous power-shovels 15 now being built, such a suspension imposes a tremendous buckling strain on the center of the boom. Accordingly we provide an additional support at that point.

During the revolution of the whole shovel 20 for dumping, the stopping and starting inertia of the dipper and its contents tends to twist the boom sidewise and also to swing the boom sidewise; to offset which tendencies, we conceived the idea of doubling the supporting means at the center of the boom, as 25 that is where the twist is imposed.

The problem of resisting torsion in the boom, we solved by widely spacing the two anchorages of this double supporting means 30 at the shipper shaft; and the problem of resisting the sidewise swinging, with respect to the revolving frame of the machine, of the entire boom about its base, we solved by 35 widely spacing the two anchorages of this double supporting means at the apex of the A-frame.

So far, all that has been said would be satisfied by having the supports which run to the outer point of the boom and the supports which run to the shipper shaft be distinct from each other; but, if so built, the difficulty would be introduced that a very nice adjustment of lengths would be frequently necessary, in order to prevent the 40 stretching of one set from imposing an undue share of the supporting duty upon the other set. This difficulty, we met by making the right-hand center-support flexible and continuous with the right-hand end-support; 45 and similarly with the two left supports. And this had the additional advantage of lending a little flexibility to the boom.

This, however, introduced a new difficulty, namely that the boom now tended to buckle 50 upward. But we discovered that, by giving to that end of the rope which supported the center of the boom fewer reaches than was given to that end which supported the point of the boom, this tendency to upward buckling would be eliminated. And this had the

added advantage of placing most of the support at the point of the boom, where it belongs.

Even so, a twist given to the center of the boom, would be translated through the suspension ropes into a reverse twist at the point of the boom. This we finally succeeded in obviating by narrowly spacing the sheaves at the end of the boom. Thus the pull imparted on the ropes by a twist at the shipper shaft, is first reduced by the larger number of reaches in that part of the ropes at the point of the boom, is further reduced by the obliqueness with which these ropes lie with respect to the boom, and then is translated into an almost negligible twist of the end of the boom by the narrow spacing of the sheaves at that point. Thus we have offset torsion at the center of the boom by very nearly a pure pull, without torsion, at the point of the boom.

By widely spacing the return of these ropes to the A-frame, we were able to provide a still further resistance to the tendency, already mentioned, of the boom to swing about its base.

Our invention consists in the solution of these successive problems.

To simplify the wording of the claims, the phrases "narrowly spaced" and "widely spaced" will be used to mean laterally so spaced.

Having now particularly described and illustrated one exemplification of our invention, we wish to be understood as not thereby limiting ourselves to the particular form shown, except in so far as such limitations are specified in the accompanying claims.

We claim:

1. In a power-shovel, having an A-frame, 105 a boom, and a shipper shaft mounted at a point intermediate the ends of the boom: a boom-suspension, consisting in two ropes, passing from points of attachment at the ends of the shipper shaft, thence over widely spaced sheaves at the apex of the A-frame, 110 thence over narrowly spaced sheaves at the outer end of the boom, and thence back to widely spaced anchorages at the apex of the A-frame.

2. In a power-shovel, having an A-frame, 115 a boom, and a dipper and dipper handle mounted on the boom for swinging in a vertical plane about a fixed axis on the boom and for reciprocation with respect to said fixed axis: a boom-suspension, consisting in two ropes, passing from widely spaced points of attachment adjacent said fixed axis, thence over widely spaced sheaves at the apex of the A-frame, 120 thence over narrowly spaced sheaves at the outer end of the boom, and thence back to widely spaced anchorages at the apex of the A-frame.

3. In a power-shovel, having an A-frame, 125 a boom, and a shipper shaft mounted at a

5 point intermediate the ends of the boom: a boom-suspension, consisting in two ropes, passing from points of attachment at the ends of the shipper shaft, thence over widely spaced sheaves at the apex of the A-frame, thence over narrowly spaced sheaves at the outer end of the boom, and thence back to anchorages at the apex of the A-frame.

10 4. In a power-shovel, having an A-frame, a boom, and a dipper and dipper handle mounted on the boom for swinging in a vertical plane about a fixed axis on the boom and for reciprocation with respect to said fixed axis: a boom-suspension, consisting in two ropes, passing from widely spaced points of attachment adjacent said fixed axis, thence over widely spaced sheaves at the apex of the A-frame, thence over narrowly spaced sheaves at the outer end of the boom, and thence back to anchorages at the apex of the A-frame.

15 5. In a power-shovel, having an A-frame, a boom, and a shipper shaft mounted at a point intermediate the ends of the boom: a boom-suspension, consisting in two ropes, passing from the ends of the shipper shaft, over widely spaced sheaves at the apex of the A-frame, to narrowly spaced points at the outer end of the boom; that part of each rope which runs from the shipper shaft to

20 the A-frame having less reaches than that part of said rope which runs from the A-frame to the outer end of the boom.

25 6. In a power-shovel, having an A-frame, a boom, and a dipper and dipper handle mounted on the boom for swinging in a vertical plane about a fixed axis on the boom and for reciprocation with respect to said fixed axis: a boom-suspension, consisting in two ropes, passing from widely spaced points adjacent said fixed axis, over widely spaced sheaves at the apex of the A-frame, to narrowly spaced points at the outer end of the boom; that part of each rope which runs from the shipper shaft to the A-frame having less reaches than that part of said rope which runs from the A-frame to the outer end of the boom.

30 7. In a power-shovel, having an A-frame, a boom, and a shipper shaft mounted at a point intermediate the ends of the boom: a boom-suspension, consisting in two ropes, passing from the ends of the shipper shaft, over widely spaced sheaves at the apex of the A-frame, to narrowly spaced points at the outer end of the boom; that part of each rope which runs from the shipper shaft to the A-frame having a single reach, and that part of said rope which runs from the A-frame to the outer end of the boom having a plurality of reaches.

35 8. In a power-shovel, having an A-frame, a boom, and a dipper and dipper handle mounted on the boom for swinging in a vertical plane about a fixed axis on the boom and for reciprocation with respect to said

fixed axis: a boom-suspension, consisting in two ropes, passing from widely spaced points adjacent said fixed axis, over widely spaced sheaves at the apex of the A-frame, to narrowly spaced points at the outer end of the boom; that part of each rope which runs from the shipper shaft to the A-frame having a single reach, and that part of said rope which runs from the A-frame to the outer end of the boom having a plurality of reaches.

40 9. In a power-shovel, having an A-frame, a boom, and a shipper shaft mounted at a point intermediate the ends of the boom: a boom-suspension, consisting in two ropes, passing from the ends of the shipper shaft, over widely spaced sheaves at the apex of the A-frame, to narrowly spaced points at the outer end of the boom.

45 10. In a power-shovel, having an A-frame, a boom, and a dipper and dipper handle mounted on the boom for swinging in a vertical plane about a fixed axis on the boom and for reciprocation with respect to said fixed axis: a boom-suspension, consisting in two ropes, passing from widely spaced points adjacent said fixed axis, over widely spaced sheaves at the apex of the A-frame, to narrowly spaced points at the outer end of the boom.

50 11. In combination: a main frame; a boom, pivoted at its foot to the frame; two sheaves at the outer end of the boom; two laterally spaced sheaves on the frame at a point higher than the pivot foot; and two boom-suspension ropes, each of which passes from one of two laterally spaced anchorages approximately midway between the ends of the boom, over one of the sheaves on the frame, thence over one of the sheaves on the boom, and thence to an anchorage on the frame, adjacent the sheaves on the frame.

55 12. In a power-shovel, having an A-frame, a boom, and a shipper shaft mounted at a point intermediate the ends of the boom: a boom-suspension, consisting in means, passing from the ends of the shipper shaft to widely spaced points at the apex of the A-frame, and in means, passing from narrowly spaced points at the outer end of the boom to widely spaced points at the apex of the A-frame.

60 13. In a power-shovel, having an A-frame, a boom, and a dipper and dipper handle mounted on the boom for swinging in a vertical plane about a fixed axis on the boom and for reciprocation with respect to said fixed axis: a boom-suspension, consisting in means, passing from widely spaced points on the boom adjacent said fixed axis to widely spaced points at the apex of the A-frame, and in means, passing from narrowly spaced points at the outer end of the boom to widely spaced points at the apex of the A-frame.

65 14. In a power shovel, having an A-frame

and a boom, the combination of: means, co-operating with the A-frame, for hoisting the boom; and a distinct means, extending from the A-frame to points adjacent the outer end of the boom and points adjacent the middle of the boom, for supporting the boom, when hoisted.

15. In a power shovel, having an A-frame and a boom, the combination of: a boom-
10 hoist cable, cooperating with the A-frame; and boom-suspension cables, extending from the A-frame to points adjacent the outer end of the boom and points adjacent the middle of the boom.

15 In testimony whereof they affix their signatures.
